UNITED STATES PATENT OFFICE.

JULIAN KAZIENKO, OF ROSEBANK, NEW YORK.

COLOR-SIFTING MACHINE.

Application filed January 22, 1924. Serial No. 687,839.

To all whom it may concern:

Be it known that I, JULIAN KAZIENKO, a citizen of Poland, residing at Rosebank, in the county of Richmond and State of New York, have invented certain new and useful Improvements in Color-Sifting Machines, of which the following is a specification.

This invention is directed to an improvement in color-sifting machines, wherein the color is worked through a screen or the like to eliminate impurities carried by the pigment.

In machines of this type, it is important that the screen element be capable of ready and convenient removal from or application to the machine, in order to provide for a change of screen when desired; and also that the spreading elements by which the material is spread over and forced through the screen, must be capable of convenient removal for cleaning and the like, or the substitution of other elements.

The present invention is directed to a machine of this character in which the receptacle is formed with an opening of such size as to permit the convenient removal therethrough of the screen or spreading elements, together with means, including a part controlled by the door for said opening, for securing the screen in place in a manner to permit its ready disconnection; and the mounting of the spreading elements so that they may be conveniently detached when desired for removal.

The invention is illustrated in the accompanying drawings, in which:

Fig. 1 is a vertical sectional view of the improved machine.

Fig. 2 is a sectional detail illustrating the means for disconnecting the spreading means from the drive shaft.

Fig. 3 is a section on line 3—3 of Fig. 1.

Fig. 4 is a section on line 4—4 of Fig. 1.

Fig. 5 is a section on line 5—5 of Fig. 3.

The improved machine comprises a container 1 preferably formed to provide a circular wall 2 and a converging or rounded bottom portion 3, the latter having an outlet 4. The container 1 is formed to provide a shoulder 5 at the juncture of the wall 2 and rounded bottom portion, this shoulder 5 being of appropriate width for supporting the screen. The container is provided with a removable cover 6 formed for the reception of an inlet 7 and centrally provided to permit the passage therethrough of a drive shaft 8, which beyond the cover is provided

with a bevel gear 9, adapted to be engaged by a bevel pinion 10 mounted on a power shaft 11, the operating mechanism being preferably supported upon a bracket 12 removably secured upon the cover 6.

The cylindrical wall 2 of the container is formed with an opening 13, which includes a considerable portion of the height of the wall and approximately half its circumferential length, providing an opening through which the screen and other operative parts may be conveniently removed or inserted. The wall 2 is provided with a door 14, swingingly mounted to close the opening 13, the door being appropriately flanged at 15 and arranged to be secured in closing position by a clamping latch 16, to secure a fluid tight connection.

The screen 17 is adapted to divide the upper portion of the container from the rounded bottom, and must be conveniently removable and replaceable, as it is necessary to use screens of different mesh with different material, and also necessary to clean a particular screen after continued use. To provide for this convenient removability of the screen, the latter is held in position between a metal ring 18 and a frame 19, which respectively overlie and underlie the peripheral edge of the screen, the frame having a ring portion resting upon the shoulder 5 in the container, when the parts are applied. The wall 2 is provided at convenient points with cam members 21, rotatably supported at 22 from said wall 2, and operative through handle projections 23 to be turned into a position to exert pressure upon the ring 18 or to release such ring. The door 14 is formed with a similar cam projection 24, to be operated by an outer handle 24', so that after closing the door, said cam 24 may be turned to overlie and bear upon the ring 18, whereby said ring and thereby the screen, are held in fixed relation on the shoulder 5.

It will be apparent from the above that by opening the door, which thereby withdraws the wedge lug or projection 24 from cooperation with the clamping ring 20, and the subsequent turning of the cam members 21, the screen may be conveniently removed for cleaning or for replacement by a screen of different character.

The pigment is subjected to a spreading and forcing action into cooperation with the screen through the medium of a spreading element, comprising a bar 25, to the oppo-

site ends of which are secured brushes or other spreading elements 26. A rod-like upright 27 projects from the bar 25, being located however, nearer to one end of said bar than the other. The upper portion of this upright is non-circular in cross section, and a sleeve 28 of similar interior form for a portion of its length is slidably mounted upon the upright, and spring pressed in the upward direction through a spring 29 coiled about the upright between the lower end of the sleeve and the bar 25. The upper portion of the sleeve is adapted to slidably fit the lower end of the drive shaft 8, and may have a key connection therewith as at 30 and be further secured by a set screw 31. Thus with the sleeve in operative relation to the drive shaft, the spreading elements are rotated coincidently with the movement of such shaft, and by the location of the brushes 26 at different distances from the center of rotation, it is apparent that the full area of the screen is operated upon by comparatively short brushes. 25 If it is desired to remove the spreading apparatus, which of course would precede the removal of the screen, the set screw 31 is disconnected and the sleeve 28 moved downwardly on the upright 27 against the tension of the spring 29, and held in its lowered position free of the drive shaft by the use of the set screw 31, as shown in Fig. 2. The spreading apparatus is thus wholly free of connection with the drive shaft and may be conveniently removed through the opening 13. It will be noted that the spring 29 exercises considerable pressure upon the bar 25 when the parts are in operative positions, thus causing a uniform pressure to be exerted on the brushes and on the material being operated on.

If desired, and as preferred, the frame 19 may be in the form of cross wires 33 defining a rectangular outline to directly underlie and support the screen 17. This frame provides a support for the intermediate portion of the screen and prevents sagging or distortion of the screen in use.

It is apparent from the above that the spreading apparatus and the screen, either or both, may be conveniently removed from the machine and as conveniently replaced, without loss of time, and without the necessity of dismantling the machine or holding the machine out of service for any considerable time.

Aside from the details herein specified, it is understood that the various parts of the apparatus may be constructed in any preferred or usual manner best adapted for the particular use for which it may be designed.

Claims:

1. A color sifting machine formed with an opening to permit the bodily removal therethrough of the sifting screen, a door

for said opening, means carried by said door to assist in securing the screen in place.

2. A color sifting machine having a screen, rings to hold the screen in place, a door closed opening formed in the machine of a size to permit the removal of the screen therethrough, and means carried in part by the door and in part by the machine proper to engage said rings to secure the screen in place.

3. A color sifting machine comprising a container formed with an interior shoulder, the wall of the container above said shoulder being formed with an elongated opening, a door for closing the opening, a sifting screen, means cooperating with the shoulder to hold the screen thereon, and means carried by the door to engage and hold said screen in place.

4. A color sifting machine comprising a container formed with an interior shoulder, the wall of the container being formed above said shoulder with an elongated opening, a ring engaging the peripheral edge of the screen, a frame underlying the screen and resting on said shoulder, and cams operatively supported on the wall of the container to engage and bear upon said ring.

5. A color sifting machine comprising a container formed with an interior shoulder, the wall of the container being formed above said shoulder with an elongated opening, means engaging the opposite sides of the peripheral edge of the screen and resting on said shoulder, cams operatively supported on the wall of the container to engage and bear upon said means, a door for said opening, and a cam on said door adapted to be operated to bear upon said means following closing of the door, to assist in holding the screen in place.

6. A color sifting machine comprising a container formed with an interior shoulder, the wall of the container being formed above said shoulder with an elongated opening, means engaging the opposite sides of the peripheral edge of the screen, the lowermost element of said means being adapted to rest on said shoulder, cams operatively supported on the wall of the container to engage and bear upon said ring, and a skeleton frame formed with said lowermost element to underlie and support the screen within said means.

7. A color sifting machine including a container, a sifting screen therein, a rotating distributor operating on the screen, said distributor comprising independent spreading elements located bodily at different radial distances from the center of rotation of the distributor.

8. A color sifting machine including a container, a sifting screen therein, a rotating distributor operating on the screen, said distributor comprising independent brushes lo-

cated at respectively different radial distances from the center of rotation of the distributor.

9. A color sifting machine comprising a container, a screen arranged therein, a drive shaft operating above the screen, and a spreading apparatus adapted for removable

connection with the drive shaft and comprising independent brushes each located at a different radial distance from the plane of the drive shaft.

In testimony whereof I affix my signature.

JULIAN KAZIENKO.
